UNITED STATES PATENT OFFICE

2,573,621

ELASTIC FLUID TURBINE

Ernest George Sterland, Cambridge, England, assignor to The English Electric Company Limited, London, England, a British company

Application March 10, 1947, Serial No. 733,663
In Great Britain March 21, 1946

2 Claims. (Cl. 253—69)

1

The invention relates to elastic fluid (steam or gas) turbines and has the object of shortening the length of such turbines required for a given number of stages.

It is known in the construction of the rotors of elastic fluid turbines to machine deep recesses between stages, so as to sub-divide the rotor into a number of discs each of which has one or more grooves machined into its periphery into which the complementarily profiled feet of blades may be inserted, which discs are integral with a common central or hub-like portion of the body. However, the gaps between the stages increase the length of the rotor and consequently of the turbine as a whole.

It has also been suggested in the construction of the rotors of such turbines to divide the rotor into disc-like portions by means of deep annular recesses, the opposing faces of such discs being suitably grooved near their periphery so that the complementarily profiled feet of blades may be inserted. However, for turbines running at relatively high speeds of revolution in which high stresses are produced in the disc-shaped portions, it is necessary in order to reduce these stresses to a minimum to shape the faces of the discs in such a way that the axial width of the discs near the bottom of the annular recess is considerably greater than near their periphery. This results in a large axial length for each stage of blading, and thus an increased length of the rotor and consequently of the turbine as a whole.

It has further been suggested in built-up rotors to arrange the rows of blades between the individual discs or rings of the rotor assembly, the lowest pressure stage disc only carrying a row of blades in addition to the interdisc blades of the previous stages.

In order to overcome the disadvantages of these previously suggested methods of construction, the following improvement has been made in the first method of construction described above, in which according to the invention deep annular recesses are machined between stages so as to sub-divide the rotor into a number of discs, each integral with the common central or hub-like portion of the body, and having one or more grooves machined in its periphery into which the complementarily profiled feet of rows of blades may be inserted. Circular grooves are machined in the opposing surfaces of at least some of the discs near their circumferences, and additional rows of blades, with their roots profiled complementarily to said grooves in order to secure fixing, are inserted into the said grooves between such adja-

2

cent discs, the rotor blades on the individual discs being arranged substantially on the centre planes of discs engaged by rotor blades inserted in the profiles between adjacent discs on both sides, and being arranged off-set from the centre planes of discs engaged on one side only by rotor blades inserted into the circumferential grooves of adjacent discs, the off-set being away from the inserted blades.

10 In order that it may be more readily understood, the invention is illustrated by way of example in the accompanying drawing, of which:

Fig. 1 is a part of an elevation in section of a turbine according to the invention, and

15 Fig. 2 is a detail on a larger scale.

The solid rotor 1 has a bore 2 for internal inspection of the forging and is sub-divided into discs 3, 4, 5, 6, by deep annular recesses 7, 8, 9, machined into the rotor body. Thus these discs

20 are integral with the solid centre portion adjacent the bore 2 of the rotor 1. The blades of four stages 11, 12, 14 and 16 of the turbine are arranged in the usual way on the discs 3, 4, 5 and 6 respectively, and additional rows of blades

25 13 and 15 are inserted into the gaps between discs 4, 5 and 5, 6 respectively. The turbine stator 20 and the guide vanes 21 to 26 for the turbine stages 11 to 16 are indicated diagrammatically for completeness but do not in themselves differ from the usual design of such components.

30 As will be seen more clearly from Fig. 2, serrations 17 are arranged in the roots of the blades, such as 15, and complementary serrations 18 in the opposite surfaces of adjacent discs, such as 5 and 6, near their circumference. The serrations 17 and 18 are interlocked and transmit forces from the turbine blades to the respective discs. Alternatively, the roots of the blades 15 or 13 may be for example T-shaped as shown for

35 40 the roots of blades 16, and engage appropriately shaped grooves on the adjacent discs instead of the serrations shown.

As will be seen from Fig. 1, the turbine blades 12 and 16 are offset from the centre planes of their respective discs 4 and 6 towards the sides away from the adjacent row of additional inserted blades 13, 15 respectively. This is done in order to balance the forces transmitted from the blades 13 and 15 to one side of each of the respective discs 4, 6. However, in a disc such as 5, having additional blades attached on both sides, the blades such as 14 are arranged substantially on the centre line.

The number of inserted stages is shown to be 55 two in Fig. 1 but obviously as many such stages

can be arranged as required by the overall number of stages and the particular design of the turbine. In the embodiment shown no such additional blades have been inserted between the stages marked 11 and 12 in order that the stresses in the disc 3 which carries the blades 11 and which is exposed to high temperatures, be kept as low as possible. However, if such considerations do not prevail, a row of additional blades could be arranged between stages 11 and 12 as well.

What I claim as my invention and desire to secure by Letters Patent is:

1. An elastic fluid turbine comprising a casing, stator blades arranged in said casing, a rotor consisting of a central body, and discs integral with the said central body, said discs being circumferentially grooved on opposing sides near the circumference thereof, rows of rotor blades having roots profiled to match the said circumferentially grooved discs secured between such adjacent discs, and a row of rotor blades arranged on each of the said discs, alternating with the said rows of rotor blades between adjacent discs, the rotor blades on the individual discs being arranged substantially on the centre planes of discs engaged by rotor blades inserted in the profiles between adjacent discs on both sides, and off-set from the centre planes of discs engaged on one side only by rotor blades inserted into the said circumferential grooves of adjacent discs, the off-set being away from the said inserted blades.

2. An elastic fluid turbine comprising a central body, and discs integral with the said central body, said discs being circumferentially grooved on opposing sides near the circumference thereof, rows of rotor blades having roots profiled to match the said circumferentially grooved discs secured between such adjacent discs, and a row of rotor blades arranged on each of the said discs, alternating with the said rows of rotor blades between adjacent discs, the rotor blades on the individual discs being arranged substantially on the centre planes of discs engaged by rotor blades inserted in the profiles between adjacent discs on both sides, and off-set from the centre planes of discs engaged on one side only by rotor blades inserted into the said circumferential grooves of adjacent discs, the off-set being away from the said inserted blades.

2. In or for an elastic fluid turbine a rotor comprising a central body and discs integral with the said central body, said discs being circumferentially grooved on opposing sides near the circumference thereof, rows of rotor blades having roots profiled to match the said circumferentially grooved discs secured between such adjacent discs, and a row of rotor blades arranged on each of the said discs, alternating with the said rows of rotor blades between adjacent discs, the rotor blades on the individual discs being arranged substantially on the centre planes of discs engaged by rotor blades inserted in the profiles between adjacent discs on both sides, and off-set from the centre planes of discs engaged on one side only by rotor blades inserted into the said circumferential grooves of adjacent discs, the off-set being away from the said inserted blades.
